SELF CLOSING GATE FAUCET

John C. Kuckhoff, Syracuse, N. Y.

Application October 18, 1932, Serial No. 638,409

8 Claims. (Cl. 251—125)

This invention relates to gate faucets such as are used on oil and gasoline containers, or drums, molasses barrels, and other containers, and of the type wherein a spring pressed gate is supported by a pivoted carrier lever, or yoke, and slides on a face on one end of the body or spigot applied to the receptacle, to open and close the passage of the body or spigot.

It has for its object, a spring means self contained with the carrier lever and the gate, for returning the carrier lever and gate to closed position when the handle of the carrier lever is released.

It further has for its object, the utilization of the spring which is normally used to press the gate against its seating surface on the spigot or body for returning the gate to closed position when the handle, or the force tending to hold the gate open, is released; and further an arrangement of this spring whereby the opening of the gate additionally tensions the spring, and the resultant force, or reaction of the spring is applied to the gate and its seat at such an inclined angle that the gate is not only pressed against its seat, but also shifted along its seat into closed position.

Other objects appear throughout the specification.

The invention consists in the novel features and in the combinations and constructions hereinafter set forth and claimed.

In describing this invention, reference is had to the accompanying drawing in which like characters designate corresponding parts in all the views.

Figures 1 and 2 are elevations, partly in section, of two exemplifications of this invention.

Figure 3 is a fragmentary plan view of the stop for limiting the opening movement of the gate in the form shown in Figure 1.

Figure 4 is a diagrammatic view illustrating the operation.

1 designates the body or spigot, this being a conduit usually threaded at one end at 2 for attachment to a receptacle or drum and having a head 3 at its other end formed with a gate face or seat 4, the passage 6 of the body opening through a port 7 through the face 4.

8 is the gate slidable over the face 4 to open and close the port 7. 9 is the carrier for the gate, this being usually a bifurcated lever or yoke extending astride the head 3 and having its arms pivoted at 10 to the head on a transverse axis, and its intermediate portion opposed to the face 4.

11 is a coil spring interposed between the intermediate part of the carrier lever 9 and the gate 8, said spring being normally under tension, and said face so extending relatively to the pivot 10 and the face 4, that movement of the carrier to open the gate additionally tensions the spring to the extent that the additional tension is sufficient to slide the gate toward closed position when the carrier is released. The carrier is formed with the usual handle 12 and is made up in the usual manner in two halves secured together as by rivets 13. The spring is also located in the usual socket 14 formed partly in both halves of the lever, and the spring at one end encircles a stud 15 on the gate 8, the stud and the spring being at an inclined angle to the face 4 and inclining in the direction of movement of the gate toward closed position.

Heretofore in this type of faucet, the gate face has been arcuate or cylindrical with the center of the arc located coincident with the axis 10 of the gate carrier or yoke, and a spring has been arranged radial to the axis or the center of the arc of the gate face, or the spring performing the sole function of pressing the gate tightly against the gate seat or face.

As seen in Figures 1 and 4, when an arcuate face, as 4, is used, the center of the arc is a different one from that of the carrier lever 9, and is here shown as located at C eccentric to and above the axis 10 so that the end portion of the face 4, through which the port 7 opens, is nearer the axis 10 than the upper end or portion of said face 4, and the spring 11 is arranged substantially radial with the axis 10. Likewise, the stud 15 on the gate is radial with the axis 10. Hence, the spring 11 thrusts on the face 4 out of a radial line, or at an inclined angle to a line radial with the axis 10, and, the face 4 having a different center than the pivot pin, the spring in reacting under its additional tension applied thereto when the gate is opened, thrusts the gate downwardly over the face 4 to closed position when the handle 12 is released.

In Figure 2, the gate face 40 is shown as flat or straight, and at an inclined angle to any radial plane from the axis 10 so that the lower end of the face 40 is nearer the axis 10 than the upper end, and the spring 11 being radial with the axis 10 is additionally tensioned when the gate is open and applies a force to the gate and to the carrier to return the gate to closed position when the handle of the carrier is released.

Gates of this type are usually provided with means by which they can be locked with a pad-

lock in closed position, and usually the carriers are formed with an upwardly extending arm 16 having a forked portion 17 movable astride a lug 18 on the upper side of the head 3, which lug is formed with a perforation 19 for receiving the shackle of a padlock when the gate is closed, the perforation being so located as to be directly in the rear of the forks 17 when the gate is closed so that the shackle of the padlock will obstruct the opening of the gate.

In the illustrated embodiment of my invention, the lug 18 is provided with laterally extending stop shoulders 20 in the rear of the perforation and in the path of the forks 17 in order to engage said forks and limit the opening movement when the valve is open, these shoulders also providing a thumb piece to be engaged by the hand of the operator when opening the gate.

In the form shown in Figure 2, the opening movement is limited by the point 21 coming in contact with the upper end of the gate 8 at 22 when the gate is opened.

In any form of the invention, the spring 11 is self contained with the carrier lever 9 and performs in addition to the usual function of pressing the gate against its seat, the function of sliding the gate and moving the carrier to closed position when the handle of the carrier is released.

30. What I claim is:

1. In a self closing gate faucet, the combination of a body having a gate face at one end, and a passage extending through the body and opening through one end portion of said face, a gate 35. slideable on said face, and a carrier for the gate pivoted to the body on a transverse axis and so arranged that movement of the carrier slides the gate over said face, the end portion of said face through which said passage opens being nearer the axis in a radial direction than the other end with a spring interposed between the carrier and the gate and acting on the gate in a direction at an inclined angle to said face and toward the end of said face nearest the axis of 45. the carrier.

2. In a self closing gate faucet, the combination of a body having a gate face at one end, and a passage extending through the body and opening through one end portion of said face, a 50. gate slideable on said face to open and close said passage, and a carrier for the gate pivoted to the body on a transverse axis and so arranged that movement of the carrier slides the gate over said face, with single spring means self contained 55. with the carrier and movable therewith and arranged to press the gate against said face, said face and the carrier being so arranged that movement of the carrier to open the gate additionally tensions the spring, whereby the spring 60. tends to move the carrier when released to slide the gate into closed position.

3. In a self closing gate faucet, the combination of a body having a gate face at one end, and a passage extending through the body and opening 65. through one end portion of said face, a gate slideable on said face to open and close said passage, and a carrier for the gate pivoted to the body on a transverse axis and so arranged that movement of the carrier slides the gate over said face, with single spring means self contained 70. with the carrier and movable therewith and arranged to press the gate against said face, said face and the carrier being so arranged that movement of the carrier to open the gate additionally tensions the spring, whereby the spring 75. tends to move the carrier when released to slide the gate into closed position.

tends to move the carrier when released to slide the gate into closed position, said spring being arranged at an inclined angle to said face, the inclination being in the direction of the gates when moving toward closed position.

4. In a self closing gate faucet, the combination of a body having a gate face at one end, and a passage through the body opening through said face, a gate slideable on said face, and a carrier for the gate pivoted to the body on a transverse axis whereby movement of the carrier slides the gate over said face to open and close said passage, with a spring interposed between the carrier and the gate, and acting in a direction at an inclined angle to said face, said face being arcuate and having its center located eccentric to the pivotal axis of the carrier, whereby one end portion of said face is located nearer the axis of the carrier than the other end, said spring acting at an inclination toward the portion of said face nearest the axis of the carrier, the passage opening through the portion of said face nearest the axis of the carrier.

5. In a self closing gate faucet, the combination of a body having a gate face at one end, and a passage extending through the body and opening through an end portion of said face, a gate slideable on said face, and a carrier for the gate pivoted to the body on a transverse axis, whereby movement of the carrier slides the gate over said face, and said face being arranged at an inclined angle to any plane radial with the axis of the carrier and intersecting said face whereby one end portion of said face is located nearer the axis of the carrier than the other end portion, said passage opening through the portion nearest said axis, and a spring carried by the carrier and arranged to thrust against the gate in a direction at an inclined angle to said face and in an inclined direction toward the portion of the face through which the passage opens.

6. In a self closing gate faucet, the combination of a body having a gate face at one end, and a passage through the body opening through one end portion of said face, a gate slideable on said face, and a carrier for the gate pivoted to the body on a transverse axis whereby movement of the carrier slides the gate over said face to open and close said passage, with a spring interposed between the carrier and the gate and acting in a direction at an inclined angle to said face, said face being arcuate and having its center located eccentric to the pivotal axis of the carrier, whereby one end of said face is located nearer the axis of the carrier than the other end, said passage opening through the end portion of said face nearest the axis of the carrier, and said spring being arranged to thrust substantially radially with the axis of the carrier.

7. In a self closing gate faucet, the combination of a body having a gate face at one end, and a passage extending through the body and opening through said face, a gate slideable on said face, and a carrier for the gate pivoted to the body on a transverse axis, whereby movement of the carrier slides the gate over said face, said face being arranged at an inclined angle to any plane radial with the axis of the carrier and intersecting said face whereby one end portion of said face is located nearer the axis of the carrier than the other end and said passage opening through the portion of said face nearer said axis, and a spring carried by

the carrier and arranged to thrust substantially radially with the axis of the carrier.

8. In a self closing gate faucet, the combination of a body having a gate face at one end, and a passage extending through the body and opening through said face, a gate slidable on said face, and a carrier for the gate pivoted to the body on a transverse axis and so arranged that movement of the carrier slides the gate over said

10 face, one end of said face being nearer the axis

in a radial direction than the other end, a spring interposed between the carrier and the gate and acting on the gate in a direction at an inclined angle to said face and toward the end of said face nearest the axis of the carrier, the gate being formed with a stud extending at an inclined angle to said gate, and radial with the axis of the carrier, the spring encircling the stud.
